BRUSH EQUIPPED RECEPTACLE

James Gannon, Far Rockaway, N. Y.

Application July 16, 1937, Serial No. 154,087

1 Claim. (Cl. 91—67.2)

This invention relates to a receptacle having a brush connected with a closure, the general object of the invention being to provide means whereby some of the contents of the receptacle 5 can be placed on the brush by simply tilting the receptacle to cause some of the contents to contact the bristles of the brush, said brush being carried by the closure of the receptacle.

Another object of the invention is to provide a 10 part in the receptacle which forms a chamber for the brush when the parts are assembled.

This invention also consists in certain other features of construction and in the combination and arrangement of several parts, to be herein- 15 after fully described, illustrated in the accompanying drawing and specifically pointed out in the appended claim.

In describing the invention in detail, reference will be had to the accompanying drawing where- 20 in like characters denote like or corresponding parts throughout the several views, and in which:—

Figure 1 is a longitudinal sectional view through a container constructed in accordance 25 with this invention, and showing the cap thereof as supporting the brush.

Figure 2 is a top plan view of the receptacle with the cap removed.

In this drawing the numeral 1 indicates the 30 receptacle which may be of any suitable type, though the drawing shows it in the shape of a jar having a screw cap 2. The brush is shown at 3 and has a groove 4 in the lower end of its handle part which is engaged by a part of the cap, the brush passing through a hole in the cap as 35 shown.

A substantially frustro-conical part 5 is formed with the mouth of the receptacle and extends 40 downwardly into the receptacle in an inverted position, the open lower end 6 of this member 5 receiving the lower end of the bristles of the brush, as shown in Figure 1.

When some of the contents of the container is to be applied to the brush it is simply necessary

to tilt the container so that some of the contents will enter the hole 6 and thus reach the bristles of the brush but when the container is in upright position the member 5 will prevent the material in the receptacle from reaching the bristles of 5 the brush.

The invention is mainly intended for use with liquid shaving soap and the like and, of course, the brush may be cleaned, after use, and then the cap is secured on the receptacle with the bristles of the brush located in the part 5.

It is thought from the foregoing description that the advantages and novel features of the invention will be readily apparent.

It is to be understood that changes may be 15 made in the construction and in the combination and arrangement of the several parts, provided that such changes fall within the scope of the appended claim.

Having described the invention, what is 20 claimed as new is:—

A combination liquid container and brush holder device adapted to be inverted to moisten the brush and comprising a jar having a body portion designed to be partially filled with liquid to a 25 maximum level, an exteriorly threaded neck on said body portion, a flanged closure cap threaded on said neck, a cup-like downwardly tapering brush guard integral with said neck and extending inwardly therefrom into the top of said body portion and having an open bottom establishing 30 said maximum level, a brush having a handle fixed in said cap to extend outwardly therefrom for unscrewing the cap and removing the brush, and a bristle assembly on said handle extending 35 inwardly into the guard and terminating at its free end close to the opening in said bottom in partially closing relation to said opening, whereby when the device is inverted said guard and end of the brush coat to limit the quantity of 40 liquid contacting said assembly and tend to prevent said liquid from moistening the sides of said assembly.

JAMES GANNON.
